UNITED STATES PATENT OFFICE

1,927,828

FURNITURE

Charles W. Greenhill, New York, N. Y.

Application April 17, 1933. Serial No. 666,481

9 Claims. (Cl. 45—106)

This invention relates to furniture and is particularly directed to a combination wardrobe and folding screen.

An object of this invention is to provide an article of furniture of the character described having a wardrobe or closet portion and provided with panels foldable against opposite sides of the wardrobe, said article being so constructed as to function as a folding screen.

10 A further object of this invention is to provide in an article of furniture of the character described, a wardrobe open on one side, and a panel foldable to close the open side of the wardrobe and movable to a position where one edge 15 of the panel is contiguous to one of the rear edges of said wardrobe.

20 A further object of this invention is to provide a compact, neat and rugged article of furniture of the character described, which shall be relatively inexpensive to manufacture, comprise few and simple parts, which shall be easy to manipulate for folding and unfolding, and which shall nevertheless be practical and efficient to a high degree.

25 Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

35 Fig. 1 is a perspective view of an article of furniture embodying the invention;

40 Fig. 2 is a perspective view of the device shown in Fig. 1 with one of the panels swung open and showing in dot dash lines the screen panels in position for use as a screen;

45 Fig. 3 is a horizontal, cross-sectional view cut through the device shown in Fig. 1 of the drawing;

Fig. 4 is a view similar to Fig. 3 but showing the screen panels in unfolded position;

50 Fig. 5 is a perspective, fragmentary detail view of one of the double hinges;

Fig. 6 is a view similar to Fig. 5 but showing the hinge in another position;

55 Fig. 7 is a partial, horizontal, cross-sectional view of an article of furniture embodying the invention, illustrating a modified construction thereof;

Fig. 8 is a view similar to Fig. 7 but showing the parts in another position; and

Fig. 9 is a perspective view of a portion of the structure shown in Fig. 7.

Referring now in detail to the drawing, 10 designates a piece of furniture embodying the invention, here shown in the form of a combination wardrobe and folding screen. The device 10 comprises a wardrobe, cabinet or closet 11 of any suitable construction, and provided with a bottom wall 12, a top wall 13, side walls 14 and 15, and a rear wall 16. The cabinet 11 may be open at the front and may be provided with a shelf 17 or with partitions, drawers, or any other interior construction.

Hinged to one of the rear edges 20 of the wardrobe 11 by a pair of double hinges 21 is a screen panel 22 foldable against the outer surface of the rear wall 16. The panel 22 is also swingable about the hinges 21 to the position shown in Fig. 2 of the drawing. It will be noted that the hinges 21 which are of well known construction, permit the panel 22 to be swung to opposite sides of the plane of the rear wall 16. Attached to the side wall 15 of the wardrobe 11, remote from the corner 20 of said wardrobe, are a pair of spaced, parallel, horizontal guide bars 23. Each bar 23 is provided with a portion parallel to and somewhat spaced from the outer surface of said side wall 15 and with end portions fastened to the front and rear edges of said side wall, in any suitable manner.

Slidably mounted on each of said bars 23 is a slider 25 to which there is attached a double hinge 21a, similar to the double hinge 21 referred to above. Mounted on the hinges 21a is a panel 27, similar to the panel 22. The sliders 25, as illustrated in Fig. 3 of the drawing, are slidably moved toward the front edge 28 of the side wall 15. In such position the panel 27 may be swung into position for covering the front open end of the wardrobe. When it is desired to use the device 10 as a screen, however, the panel 22 may be swung to the position shown in Fig. 2 in dot dash lines, and the panel 27 may be swung open and the sliders 25 moved rearwardly to carry the panel 27 to the position shown in Fig. 4. The panel 27 may then be swung about the rear right corner 30 of the wardrobe to the position shown in dot dash lines in Fig. 2 of the drawing. In such position, the device may be used as a screen. Thus a person may keep clothing in the wardrobe which may be closed compactly, as shown in Fig. 1 of the drawing. The device may be opened and used as a screen, and the person

standing in front of the wardrobe may remove clothing from the wardrobe while being screened.

In Figs. 7, 8 and 9 there is shown a combination wardrobe and screen 10a embodying the invention and illustrating a modified construction thereof. The device 10a comprises a wardrobe 11a having a rear wall 16a and side walls 15a, and preferably being open at the front.

Hinged to one of the rear corners of the wardrobe in a manner similar to that shown in Figs. 1 to 4, is a panel 22a similar to the panel 22 and foldable against the rear wall 16a of the wardrobe. Attached to the side wall 15a, however, are a pair of spaced, vertically aligned, upper and lower hinges 35. To one leaf of each of said hinges there is soldered, riveted or otherwise attached, a plate or bar 36. The hinges 35 are preferably located substantially on the mid-section of the side wall 15a, and each bar 36 is of a length substantially equal to half the width of said side wall 15a. Attached to the outer end 37 of each plate 36 is a double hinge 21b similar to the hinges 21a and 21. Attached to the hinges 21b is a screen panel 38 swingable into position for covering the front side of the wardrobe 11a.

As shown in Fig. 7 of the drawing, the plates 36 are swung to extend from the hinge 35 toward the front edge 28a of the side wall 15a, and the panel 38 is swung into position for closing the front side of the wardrobe. As shown in Fig. 8 of the drawing, the plates 36 are swung to extend from the hinges 35 toward the rear edge 30a of the side wall 15a, and the panel 38 is swung about the hinges 21b into position for use as a screen.

For retaining the plates 36 in either the position shown in Fig. 7 or Fig. 8, said plates are each provided with a horizontal slot 40. Attached to the inner surface of the side wall 15a and disposed on opposite sides of each hinge 35, are a pair of spaced, aligned plates 44 and 45, each provided with a screw threaded opening. Screwed to said screw threaded openings and extending through suitable openings in said side wall 15a are screws 46 and 47 having winged heads 48 and 49, respectively. The screws 46 and 47 may be turned to bring the heads 48 and 49 into position for extending through the slot 40. Thus when moving the panel 38 from the position shown in Fig. 7 to the position shown in Fig. 8, the heads 48 of the screws 46 are first turned to horizontal position to permit the plates 36 to be swung through 180° to the position shown in Fig. 8. The heads 49 will pass through the slots 40 as the plates are swung to the position shown in Fig. 8. Said heads 49 may then be turned into vertical position for engaging the plates to retain the same against movement. It will be understood that there are provided two screws 46 and 47 for each plate 36.

It will thus be seen that there is provided a device in which the several objects of this invention are achieved, and which is well adapted to meet the conditions of practical use.

As various possible embodiments might be made of the above invention, and as various changes might be made in the embodiments set forth, it is to be understood that all matter herein set forth or shown in the accompanying drawing is to be interpreted as illustrative and not in a limiting sense.

Having thus described my invention, I claim as new and desire to secure by Letters Patent:

1. An article of furniture of the character de-

scribed comprising a cabinet open at the front, a panel hinged to one of the rear edges of the cabinet, and a panel mounted on a hinge and swingable to close the front open side of the cabinet, said hinge being movable to the other rear edge of the cabinet whereby said second panel may be swung about said other rear edge of said cabinet.

2. A combination wardrobe and screen comprising a wardrobe cabinet, a panel swingable about one rear edge of said cabinet against the rear side of said cabinet, and a second panel swingable about the other rear edge of said cabinet and being movable for closing the front open side of said cabinet.

3. In combination, a cabinet having a side wall, a member attached to said side wall and disposed parallel to said side wall, a member slidably mounted on said first member, a hinge attached to said second member, and a panel mounted on said hinge.

4. In combination, a cabinet having an open front side, a panel pivoted about one edge and adapted to close the front open side of said cabinet, said panel being swingable to bring said pivoted edge thereof contiguous to a rear edge of said cabinet.

5. A cabinet open at the front, a panel hinged to one of the rear edges of said cabinet and being swingable against the rear wall of said cabinet, a plate hinged at the inner end thereof to substantially the mid portion of the side wall of said cabinet, remote from said rear edge, said plate being swingable to extend toward the front and rear edges, respectively, of said side wall, and a panel hinged to the outer end of said plate adapted to cover the front of said cabinet when said plate extends toward the front edge of said side wall, and said second panel being adapted to swing about the rear edge of said side wall when said plate extends toward said rear edge of said side wall.

6. A cabinet open at the front, a panel hinged to one of the rear edges of said cabinet and being swingable against the rear wall of said cabinet, a plate hinged at the inner end thereof to substantially the mid portion of the side wall of said cabinet remote from said rear edge, said plate being swingable to extend toward the front and rear edges, respectively, of said side wall, and a panel hinged to the outer end of said plate adapted to cover the front of said cabinet when said plate extends toward the front edge of said side wall, and said second panel being adapted to swing about the rear edge of said side wall when said plate extends toward said rear edge of said side wall, and means for retaining said plate against swinging movement.

7. A cabinet open at the front, a panel hinged to one of the rear edges of said cabinet and being swingable against the rear wall of said cabinet, a plate hinged at the inner end thereof to substantially the mid portion of the side wall of said cabinet remote from said rear edge, said plate being swingable to extend toward the front and rear edges, respectively, of said side wall, and a panel hinged to the outer end of said plate adapted to cover the front of said cabinet when said plate extends toward the front edge of said side wall, and said second panel being adapted to swing about the rear edge of said side wall when said plate extends toward said rear edge of said side wall, and means for retaining said plate against swinging movement, said means

comprising a member having a head rotatably mounted on said side wall, said plate having a slot therein adapted to receive said head.

8. In combination, a cabinet having a side wall 5 and being open at the front and closed at the rear, a member hinged at one end thereof to said side wall at the longitudinal mid portion of the latter, said member having a length substantially equal to one half the width of said side wall, 10 and said member being swingable to bring the outer end thereof to the front and rear edges of said side wall, and a screening panel hinged to the outer end of said member and adapted to cover the front open side of the cabinet in one 15 position thereof and adapted to contact the rear side edge of said side wall in another position thereof.

9. In combination, a cabinet having a side wall, and being open at the front and closed at the rear, a member hinged at one end thereof to said side wall at the longitudinal mid portion of the latter, said member having a length substantially equal to one half the width of said side wall, and said member being swingable to bring the outer end thereof to the front and rear edges of said side wall, and a screening panel hinged to the outer end of said member and adapted to cover the front open side of the cabinet in one position thereof and adapted to contact the rear side edge of said side wall in another position thereof, and means for retaining said member against said side wall.
